UNITED STATES PATENT OFFICE.

JENS HANSEN, OF SUPERIOR, WISCONSIN.

PORTABLE DERRICK.

Application filed April 21, 1923. Serial No. 633,779.

This invention relates to an improvement in portable derricks, designed for complete flexibility in adjustment for operation, being adapted for rotation, weight-compensating adjustment, and load handling through control means within convenient accessibility of a single operator.

The improved derrick includes a load beam, at one end of which is arranged load handling means capable of adjustment longitudinally of the beam. The opposite end of the load beam is provided with a load compensating weight, capable of adjustment longitudinally of the beam to vary its compensating effect on the load in accordance with the weight of that load. Thus, the derrick is adapted to handle loads which ordinarily could not be taken care of without the adjustable compensating weight.

20. The load beam is adapted for rotation about a fixed standard or mast, and this rotation is controlled at will and in degree by the operator, and the movably-supported base for the derrick is provided with means whereby the derrick may be shifted from place to place, as desired.

The invention is illustrated in the accompanying drawings, showing the preferred construction, and in which:

30. Fig. 1 is a perspective view of the improved derrick.

Fig. 2 is a longitudinal section through the load beam.

Fig. 3 is a transverse section taken just above the platform.

Fig. 4 is a sectional view, showing the platform mounting.

40. The improved derrick comprises a base 1, preferably of skeleton metallic formation, mounted on self-adjusting wheels or rollers 2, to permit movement of the derrick from place to place.

A bed plate 3 is supported above the base by inclined struts 4 rising from the base, and a mast 5 is secured in a block 6, carried by a cross frame secured to the base, the mast rising through the bed plate to an appropriate height, and being thus fixed with relation to the base 1.

50. The movable portion of the derrick superstructure is mounted for rotation relative to the mast, and comprises a platform 7, supported on the bed plate 3 through a ball bearing 8, and a load-beam 9 arranged near the upper end of the mast, and supported

from the platform 7 by inclined framing bars 10.

The load beam comprises a skeleton framework, preferably rectangular, and provided with a sleeve bearing portion 11 having ball-bearing connection at the upper and lower ends with the mast, the sleeve including an upper plate 12 from which the load beam is supported by hanger braces 13, and a lower plate 14 on which the beam rests.

60. It is to be particularly noted that the load beam is of unequal lengths on the respective sides of the mast-bearing sleeve, the one or load side, indicated generally at 15 being of less length than the other or compensating side, indicated at 16. The frame bars making up the load beam proper are angle bars, the horizontal portions forming trackways 17, while the vertical portions are connected with the upper sleeve plate 12 by adjustable 65 tie bars 18.

70. The superstructure is thus freely rotatable about the mast as an axis to position the load beam for picking up or delivering the load, and the load beam is manually controlled in this turning movement, through a rod mounted at the upper end in the lower sleeve plate 14, and at the lower end in one of the side plates 19 connecting the inclined framing bars 10 on each side. This rod 20 is provided near the upper end with a pinion 21, adapted to engage a gear secured on the mast 5, a pinion 22 being secured on the rod near the lower end to engage a gear 23 supported in one of the side plates 19. 80 The shaft of the gear 23 extends beyond the side plate and is shaped to receive a handle 24, whereby the rod may be turned, and thus the superstructure moved on the mast as a center to any desired position.

85. The trackways 17 of the load beam support two carriages 25 and 26 for travel on opposite sides of the sleeve 11, one carriage 25 being hereinafter termed the load carriage, and the other, 26, being hereinafter termed the compensating carriage. These carriages are substantially identical in construction, and comprise bodies 27, having end shafts or axles 28, carrying wheels or rollers 29 for free travel on the trackways 17.

100. The carriages are designed to be adjusted lengthwise the trackways in accordance with conditions, as hereinafter pointed out, and this adjusting means is designed for control by the operator. In the case of the load car-

- riage 25, an operating cable 30 is terminally wound about one drum 31 of a two-drum shaft 32 mounted in the side plates 19, this cable 30 extending upwardly and over one 5 pulley of a three-pulley block 33 secured to a collar 34 fixed to the sleeve 11. The cable 30 then extends over a pulley of a two-pulley block 35 secured to one end of the carriage, then over a second pulley of block 33, then 10 over the second pulley of block 35, and terminally secured to the carriage. The remaining cable for this load carriage, as 36, is reversely wound about the other drum 37 on shaft 32, and extends upwardly over the 15 remaining block of the pulley block 33, thence to the extreme end of the load side of the beam, over a pulley of a two-pulley block 38, secured to the load beam, rearwardly to and over a pulley of a two-pulley block 20 39, secured to the proximate end of the carriage, then forwardly over the remaining pulley of block 38, back over the remaining pulley of block 39, and terminally secured to the carriage.
- 25 The compensating carriage is arranged for control in an identical manner; that is a cable 40 is mounted on one drum 41 of a two-drum shaft 42 mounted in the side plates 19, this cable cooperating with a pulley-block 30 43 on the sleeve 11 and a pulley block 44 on the compensating carriage, similar to the connection of the cable 30 with the load carriage. A second cable 45, wound about the second drum 46 of shaft 42, cooperates with 25 the pulley block 43, with pulley block 47 at the end of the load beam, and with a pulley block 48 on the carriage, the arrangement being similar to the connection of the cable 36 with carriage 25.
- 40 The drum shafts 32 and 42 have geared connection with adjacent countershafts 49 and 50, respectively, these counter shafts being mounted in the side plates 19, and being formed beyond one of such plates for the 45 reception of operating handles, whereby the carriages may be moved to any desired position lengthwise the trackways 17, as will be evident.
- 50 A load lifting means, such as a cable 51 is suspended from the load carriage 25, and desired pulley-multiplication for this cable being provided, and the end of the cable being wound over a drum 52 on shaft 53, mounted in the side plates 19, and geared 55 to a countershaft 54 mounted in the side plates and adapted for operation by a handle. The upper and lower pulley-blocks of the load cable are provided with means, one for removable connection with the carriage 60 and the other with a load hook 55, or the like.
- 65 The compensating carriage is provided with a compensating weight 56, preferably hung therefrom in a manner to permit its replacement when necessary. This weight

acts as a counterbalance to the load being lifted, and it is apparent that by moving the respective carriages to appropriate relative distances from the sleeve 11, the weight may be made to counterbalance any load.

The load end of the beam is of less length than the compensating end, and hence the weight may be positioned through movement of the carriage on which it is supported to different distances from the sleeve 11, and thus offset the weight effect of the particular load on the beam. This arrangement permits the derrick to handle loads which it could not otherwise handle without tipping the load beam.

The derrick as a whole is adapted to be moved from place to place, and for convenience in shifting the derrick the load cable drum shaft 53 is extended and provided with a concave drum 57, over which a shifting cable 58 is wound, the base having guiding pulleys 59 through which the cable may be passed to center the same relative to the base. The end of the cable 58 is designed to be temporarily secured to any suitable fixture, as 90 60, for an anchorage in shifting. The platform 7 is positioned above the base a sufficient distance to allow the operator positioned on such platform a view of the work in hand, and may be convenient of access 95 through a ladder or steps 61.

It is to be particularly noted that the control of both carriages, the control of the load cable, and the turning of the superstructure as a whole, is within the convenient reach and government of a single operator, thus enabling one man to arrange the counterbalance and position the load carriage, operate the load lifting cable, and turn the superstructure, through manipulation of the proper crank handles, without leaving his position on the platform.

Having thus described the invention, what is claimed as new, is:—

1. In a portable derrick, a movable base, a mast rising therefrom and rigidly secured thereto, a platform rotatable on the mast above the base, a load beam rotatable on the mast above the platform, means for rotatably supporting the beam at spaced points on the mast, and bearings interposed at such spaced points and below the platform.

2. In a portable derrick, a base, a mast secured thereto and rising therefrom, a bed plate encircling the mast and carried by the base, a platform supported for rotative movement on said bed plate and relative to the mast, a bearing between the platform and bed plate, a load beam extending in both directions beyond the mast, a sleeve forming part of said load beam and adapted to be arranged in alignment with the mast, and upper and lower bearings between said sleeve and mast.

3. In a portable derrick, a base, a mast

secured thereto and rising therefrom, a bed plate encircling the mast and carried by the base, a platform supported for rotative movement on said bed plate and relative to the mast, a bearing between the platform and bed plate, a load beam extending in both directions beyond the mast, a sleeve forming part of said load beam and adapted to be arranged in alignment with the mast, upper and lower bearings between said sleeve and mast, frame bars arranged intermediate the platform and load beam to rigidly connect such parts as a unitary structure, and tie bars projecting from the upper end of the sleeve to the load beam to support the latter.

4. In a portable derrick, a base, a mast secured thereto and rising therefrom, a bed

plate encircling the mast and carried by the base, a platform supported for rotative movement on said bed plate and relative to the mast, a bearing between the platform and bed plate, a load beam extending in both directions beyond the mast, a sleeve forming part of said load beam and adapted to be arranged in alignment with the mast, upper and lower bearings between said sleeve and mast, and means for rotating the platform and load beam including a rod movable with the platform and independently rotatable, means for rotating the rod, a pinion carried by the upper end of the rod, and a gear fixed on the mast to be engaged by the pinion.

In testimony whereof, I affix my signature.

JENS HANSEN.
